UNITED STATES PATENT OFFICE.

THEODORE A. BOOR, OF ASHVILLE, OHIO.

STARTER FOR INTERNAL-COMBUSTION ENGINES.

1,103,736.

Specification of Letters Patent. Patented July 14, 1914.

Application filed November 8, 1912. Serial No. 739,171.

To all whom it may concern:

Be it known that I, THEODORE A. Boor, a citizen of the United States, and a resident of Ashville, in the county of Pickaway 5 and State of Ohio, have invented a new and Improved Starter for Internal-Combustion Engines, of which the following is a full, clear, and exact description.

My invention relates to an improvement 10 in starting devices for internal combustion engines, and the object thereof is to provide a separate motor which can be operated by means of a suitable motive agent, such as compressed air, and which is geared to the 15 starting shaft of the engine in such a way that it can turn the same to set the engine running, and then be operated in its turn by the engine crank shaft as a pump to store up air in a storage tank connected thereto 20 for further use.

Reference is to be had to the accompanying drawings forming a part of this specification, in which the same characters of reference indicate the same parts in all the 25 views.

Figure 1 represents a side elevation of my invention; Fig. 2 is a longitudinal sectional view of the air motor and transmission gearing; Fig. 3 is a sectional view on the line 30 3-3 of Fig. 2; Fig. 4 is an end view of the air motor; Fig. 5 is a top plan of the transmission gearing, showing the clutches comprised in the same in one position; and Fig. 6 is a view of the same parts, showing 35 the clutch mechanism in another position.

My invention can be applied to any kind of internal combustion engine 1 and the starting motor 2 is located, preferably beside the crank case of this engine and geared to the 40 main shaft by means of gearing indicated as a whole by the numeral 3. This gearing comprises a number of clutches so arranged that the motor can be made to drive the engine at the start, and after that the engine 45 drives the motor as a pump, to store up the compressed air needed to operate the starting motor, in a suitable tank or reservoir to which the starting motor is connected. This tank or reservoir is not shown 50 on the drawings, but it is connected to the motor 2 by means of a pipe 4, in which is a valve casing 5. This casing contains a valve that is controlled by a lever 6 mounted in suitable position, such as the dash of an 55 automobile, when the starter is used on automobiles; and the valve itself comprises a

valve body 7, held to its seat by means of a spring 8 and opened against the force of the spring by a rod 9 operated by a bell-crank lever 10. This bell-crank lever is rigidly 60 mounted upon a spindle 11, upon which the lever 6 is also secured. This lever carries 65 pedals 12 and 13, and when the former is depressed the valve is opened, and when the latter is depressed the spring 8 is free to 70 close the valve. The air motor 2 comprises any number of cylinders and is provided with a valve chest 14, from which communication is had to each of the cylinders by means of valves 15 held in closed position 75 by springs 16 and controlling inlet passages 17. These valves are operated by rods 18 and engaged by cams 19 on the main shaft 20 of the air motor, and each cylinder of the air motor is provided with a piston 21 connected to the crank shaft 20 by means of rods 22. The air enters each cylinder in turn, as the valve closing the passage 17 is opened, forcing the piston 21 therein outward to such an extent as to uncover the 80 exhaust passage 23 at the end of its stroke and allow the air to escape. The motion of the shaft 20 of the air motor 2 is communicated to the crank shaft of the engine by suitable gear wheels and clutches, as above 85 stated. This transmission mechanism includes a pinion 24 on the outer end of the shaft 20, which drives a gear wheel 25 mounted on a stud 26 projecting from the framework of the engine 1. Integral with 90 this gear wheel 25 is a clutch member 27 which engages with a clutch member 28 carried by another wheel 29 having flanges 30. These wheels 25 and 29 turn loosely on the 95 spindle or stud 26.

The main shaft of the engine receives motion from the pinion 29 by means of a gear wheel 31 mounted on the engine crank shaft 32, so as to be able to turn freely with respect to this crank shaft. The engine crank shaft is provided with a clutch member 33 secured thereto, which meshes with a clutch member 34 forming the hub of the gear wheel 31, and this clutch member 34 has clutch teeth at its opposite end to 100 mesh with another clutch 35 carried by the shaft 32. The clutch teeth on the clutch 34 which mesh with the clutch 33 are arranged to drive the shaft 32 clockwise, and when the clutch 34 is moved out of engagement with the clutch 33, and into engagement with the clutch 35, the intermeshing teeth on the 105

clutch 34 and clutch 35 will enable the crank shaft 32 to turn the gear 31, being designed to give this mode of operation. The shaft 20 on the motor 2 also carries a gear wheel 5 36 with which the gear 31 comes into mesh when the clutches 34 and 35 are interlocked. The sliding movement necessary to operate the clutch 34 in both directions is effected by means of a fork 37 carried on the end of a 10 rod 38. This rod is mounted in bearings on the framework of the motor or engine and is connected by means of a link 39 to a pin or bolt 40 at the lower end of the bell-crank lever 10.

15 In operation, when it is desired to start the engine, the pedal 12 is depressed, opening the valve 7 and allowing air to flow into the cylinders of the air motor. The same movement of the lever 6 withdraws the rod 20 38, moving the gear 31 and with it the pinion 29, because of the disks or flanges 30, in such a direction as to cause the clutches 33 and 34 and 27 and 28 to come into engaged relation. The pinion 24 now turns the gear 25 25, and through the clutches 27 and 28 the pinion 29. This pinion 29 turns the gear 31, which transmits motion through the clutches 33 and 34 to the crank shaft of the engine. After the engine 1 is running, the 30 operator depresses the pedal 13, allowing the spring 8 to close the valve 7 and move the rod 38 in the opposite direction. The gear wheels 29 and 31 now move to the left, referring to Fig. 2, bringing the gear 31 into 35 mesh with the gear 36, and the clutch 34 into mesh with the clutch 35. The engine shaft 32 now transmits motion to the motor shaft 20, and the motor 2 operates as a pump, storing up air in the reservoir connected to the pipe 4, and thus replenishing the supply of compressed air, so that the engine can be again started after stopping. During this latter operation valve 7 opens 40 under a pressure from the pump to permit 45 of the passage of air to the reservoir.

I wish to have it understood that the above description is illustrative only and discloses but one embodiment of my invention, and that I do not care to be limited to 50 the exact details shown and described, but reserve to myself the right to make such changes in the shape, size, and arrangement of the parts as fairly fall within the scope and spirit of my invention.

55 Having thus described my invention, I claim as new and desire to secure by Letters Patent:

1. In a starter for internal combustion engines, an intermediately pivoted foot 60 treadle, a spindle on which the foot treadle is secured, a bell-crank secured upon said

spindle, a valve operated by one arm of said bell-crank to supply motive fluid to a motor, and gearing operated by the other arm of said bell-crank to connect said motor to the power shaft of the engine to start the same, or to connect the power shaft of the engine to the motor to run the motor as a compressor after the engine has been started.

2. A motor having a power shaft, a pinion 70 carried thereby, a gear operated by said pinion, a clutch member carried by said gear, a pinion having a clutch member adapted to mesh with the first named clutch member, a gear meshing with said second named pinion, an engine-driven power shaft, a clutch for connecting the last named gear to the said power shaft, and means for moving said second named pinion and gear to throw said clutch and clutch members into and out of operation.

3. A starter for internal combustion engines, comprising a motor, a pinion and a gear mounted upon the shaft thereof, a gear meshing with the pinion and having a clutch member, a second pinion having a clutch member to engage the first clutch member, an engine-driven power shaft, a pair of clutch members carried by the said power shaft, a gear mounted on the power shaft between said clutch members and having clutch members to engage each of the members on the power shaft, said last named gear meshing with the second named pinion, and means for moving said second named pinion and the engine shaft gear to enable the motor to drive the engine to start the same, and the engine to drive the motor as a compressor after starting.

4. A starter for internal combustion engines, comprising a motor, a pinion mounted on the shaft thereof, an intermediate gear and pinion, the former of which meshes with the shaft pinion, a clutch adapted to connect said intermediate gear and pinion, 100 an engine-driven power shaft, a gear mounted on the said power shaft and in engagement and movable with the intermediate pinion, a gear mounted on the motor shaft and with which the engine shaft gear is 105 adapted to mesh when the intermediate gear and pinion are disengaged, and clutches for connecting the engine shaft gear with the engine shaft in relatively opposite directions, all for the purpose described.

In testimony whereof I have signed my name to this specification in the presence of two subscribing witnesses.

THEODORE A. BOOR.
